(57) **CLAIM**

The ornamental design for an oral care apparatus, as shown and described.

DESCRIPTION

FIG. 1 is a front right perspective view of an oral care apparatus according to a first embodiment of the new design; FIG. 2 is a front view thereof;

FIG. 3 is a rear view thereof;

FIG. 4 is a right side view thereof;

FIG. 5 is a left side view thereof;

FIG. 6 is an enlarged top view thereof;

FIG. 7 is an enlarged bottom view thereof;

FIG. 8 is a front right perspective view of an oral care apparatus according to a second embodiment of the new design;

FIG. 9 is a front view thereof;

FIG. 10 is a rear view thereof;

FIG. 11 is a right side view thereof;

FIG. 12 is a left side view thereof;

FIG. 13 is an enlarged top view thereof; and,

FIG. 14 is an enlarged bottom view thereof.

The broken lines in the drawings illustrate portions of the article that form no part of the claimed design.

1 Claim, 8 Drawing Sheets# US D893,881 S
